UNITED STATES PATENT OFFICE

107,399

DESIGN FOR A COVER PLATE FOR AIR EXHAUSTING DEVICE

Harry Broadwin, Brooklyn, N. Y.

Application June 26, 1937, Serial No. 70,067

Term of patent 14 years

To all whom it may concern:

Be it known that I, Harry Broadwin, a citizen of the United States and resident of Brooklyn, in the county of Kings and State of New York, have invented a new, original, and ornamental Design for a Cover Plate for Air Exhausting Device, of which the following is a specification; reference being had to the accompanying drawing, forming a part thereof.

Figure 1 represents a top plan view of a cover plate for air exhausting device showing my new

design, and Figure 2 represents a transverse section taken in the plane of the line II II of Figure 1, looking in the direction of the arrows; the chief feature of the design residing in a star figure having alternating long and short points.

I claim:

The ornamental design for a cover plate for air exhausting device substantially as shown and described.

HARRY BROADWIN.
